UNITED STATES PATENT OFFICE.

WILLIAM H. DOUGLASS, OF PHILADELPHIA, PA., ASSIGNOR TO THE NORTH AMERICAN PETROLEUM GAS COMPANY, OF NEW YORK, N. Y.

APPARATUS FOR THE MANUFACTURE OF ILLUMINATING-GAS.

SPECIFICATION forming part of Letters Patent No. 298,854, dated February 19, 1884.

Application filed May 25, 1883. (No model.)

To all whom it may concern:

Be it known that I, WILLIAM H. DOUGLASS, a citizen of the United States, residing at Philadelphia, in the county of Philadelphia and State of Pennsylvania, have invented new and useful Improvements in Apparatus for the Manufacture of Illuminating-Gas, of which the following is a specification.

My invention relates to the manufacture of illuminating-gas from substances suitable therefor of a solid, semi-solid, or liquid form, such as, for illustration, resins of commerce and fats, together with various hydrocarbons, such as petroleum and its distillates and other oils. In treating the substances referred to in order to eliminate therefrom the olefiant or illuminating principles, they have to be subjected to what is known as the "destructive-distillation process," and in carrying out that process one form of retort was employed when the solid gas-producing substance was used, and a different form when the liquid gas-producing substance was used.

My invention has for its objects the production of a generator in which the gas can be produced from either a solid, semi-solid, or liquid substance, as found desirable or convenient, and in which there is a preliminary disassociation of the component parts of the solid or semi-solid substances employed, so that only the liquefied parts of the substances will be fed to the retort in regulated quantities, while the residuary matter may be removed; and to these ends it consists in the means hereinafter particularly set forth, whereby an illuminating-gas of great purity and brilliancy is produced.

In the accompanying drawings, Figure 1 is a perspective view of an apparatus constructed according to my invention. Fig. 2 is a vertical section through the same, and Fig. 3 is a plan of the slotted flange on which the retort is supported.

Referring to said drawings, the letter A indicates the casing of the stove or heater provided with a fire-box, B, a grate, C, an ash-pit, D, and a smoke-flue, E, and preferably made in cross-sections, so that the upper section may be lifted or removed to permit ac-

cess to the retort, for purposes hereinafter appearing. Within the lower part of the casing there is a sheet or cast metal retort, F, which rests by flanges *a* on a flange or ring, G, extending inwardly from the sides of the casing, so as to divide the casing into two chambers, 55 one above and the other below the retorts, both of which communicate with the smoke-flue, as shown, and also with each other, through openings or slots *b*, made in the ring or flange G, which openings may be provided with sliding or pivoted dampers or valves, so as to permit the products of combustion and heat to pass through both the upper and lower chambers of the casing, or through only the lower chamber, as desired. The retort is of 65 cylindrical or other appropriate form, closed at bottom, and provided with a removable cover, which, when in place, completely closes the upper portion of the retort, and has a groove, *c*, formed in its flange *a*, designed to hold a 70 quantity of metal alloy reducible at a low temperature, which will form a seal between the retorts and the reservoir H when the downwardly-projecting rim *d* of the latter is set into the alloy. The retort is provided within its 75 interior with a series of horizontal plates, I, each one of which is formed with a cup or groove, *e*, on its top face, around its edge, and also, with the exception of the lowermost, which has legs resting on the bottom of the 80 retorts, with a downwardly-projecting rim, *e'*, which rests in the groove or cup of the plate next below, so that when the grooves or cups are filled with sand, plaster-of-paris, pumice-stone, or other suitable material, a seal will 85 be effected, so as to close all communication between the chambers themselves formed by the plates and the chambers and the sides of the retort, except through the openings *f*, formed in the plates at alternate ends. The plates 90 are provided each with a lifting-ring, *g*, and the series is held together by rods *J*, passed vertically through them, and provided with heads at one end and nuts at the other, so that the whole series of plates can be lifted together 95 or separately by unscrewing the nuts and raising the plate from off the rods. The retort is provided, preferably near its upper end, with

an evacuating-tube, K, provided with a cup or groove around its mouth, to receive a sealing material and the end of the pipe L, which conducts the gas to an ordinary washer, (not shown,) and which is provided with a cock to regulate the flow of gas.

The reservoir H, in addition to the rim d, formed by the extension of its sides, is provided with a downwardly-projecting flange, d', 10 which fits into the cup or groove of the plate beneath, containing sealing material, like the other cups. The reservoir fitted to the retort, as described, forms a detachable cover therefor, and communicates with the top chamber of the 15 retort through an opening, h, in its bottom, controlled by a valve, i, operated by a rod, M, passed through a threaded gland, i', at the top of the reservoir, and out through the casing C, where it is provided with any suitable hand 20 device for turning it to regulate the flow of the liquid gas-producing material from the reservoir into the retort. The bottom of the reservoir is concaved or depressed at the center, so as to facilitate the flow of oil from the reservoir into the retort, and above the concave bottom is a slatted or reticulated false bottom, N, on which the solid or semi-solid gas-producing substance is placed during the process 25 of liquefying it, and which holds the residuum 30 and prevents it from passing onto the concave bottom and into the retort. The gas-producing substance is introduced into the reservoir through the tube O, which passes through the casing C, and is provided around its mouth 35 with a cup or groove to hold a sealing material—such as moistened clay or something else as suitable—and to receive the rim or flange of the cover P, which is provided with hinged ends adapted to engage with staples on the 40 tube, and by pins held in place. The material, after its introduction into the reservoir, is liquefied by heat radiated from the retort against the bottom of the reservoir, or by the heat and products of combustion arising from 45 the fire-box upward around the retort, and through the slotted ring or flange to and around the reservoir in the space between it and the casing, and whatever matter evolved from the liquefying material that should be allowed to 50 escape finds its exit through a trap or siphon overflow-pipe, P', which holds any suitable liquid that will prevent the inflow of air or escape of gas, and which is located by preference below the tube O, and adapted to be connected 55 outside of the casing with a pipe for conducting the evolved matters to any desired point. In order to obtain a somewhat equalized pressure throughout the retort and reservoir, so as to maintain a satisfactory flow of 60 oil from the reservoir into the retort, a pipe or tube, Q, is extended from the retort through the bottom of the reservoir and upward into the tube O. When hydrocarbons of a liquid form are to be used instead of the other substances, they are introduced through a pipe, R, which extends from near the bottom of the

reservoir to outside of the casing, where it will be connected to a pipe leading from the source of supply, and the flow of the oil through said pipe into the reservoir will be controlled by a 70 cock in the valve.

In operation the valve i is closed and the reservoir filled to less than half of its capacity—say to about one-quarter of its capacity—with the solid or semi-solid gas-producing material, so as to allow for its expansion, and the tube O closed. The fire is then started, and when the retort reaches a cherry-red heat the valve i is opened, and the liquid from the gas-producing substance will run into 80 the top chamber of the retort, and there be converted into a vapor, and from thence it will pass into each successive chamber, and from the lowermost chamber between its legs into the space between the retort and casing, from 85 whence it issues through the evacuating-tube a perfectly-fixed gas, its conversion into a fixed gas being by graduated stages. The gas passes from the evacuating-tube into an ordinary washer, (not shown,) and from thence to the 90 gas-holder, and after a sufficient quantity has been generated the valve i is closed and the generator allowed to cool. When the generator is to be freed from the residuum deposited therein, the upper part of the casing 95 is detached and the reservoir lifted, so as to allow the free ingress of air to the retort, which will sustain combustion to such an extent that the residuary matter will be converted into flame and ash, and the latter can be readily 100 removed when the retort becomes sufficiently cool to admit thereof.

Having thus described my invention, what I claim is—

1. The casing having at or near its center 105 a ring or flange provided with perforations, a retort suspended from such ring and containing a series of plates having alternating openings, a pipe leading from the retort for carrying off the gas, a reservoir having a rim forming a cover to the retort, and having a bottom provided with a valve-opening, a valve for controlling said opening to regulate the supply of gas-producing material to the retort, a reticulated false bottom in the reservoir above its 110 main bottom, and means for charging the reservoir, substantially as described.

2. In a hydrocarbon-gas generator, a retort provided with a seal-cup at its upper end, a series of communicating vaporizing-chambers, 115 and an evacuating-tube communicating therewith, in combination with a reservoir fitting in the seal-cup of the retort, and provided with a valved opening communicating with the retort, a supplemental grated or reticulated bottom, and means for supplying either liquid or other gas-producing substances thereto, substantially as described.

3. In a hydrocarbon-gas generator, the retort provided with a series of vaporizing-chambers, 120 and a seal-cup to both the retort and partition-plate of the top chamber, in combination with

the reservoir, provided with a pendent rim and flange to fit into said cups, substantially as described.

4. In a hydrocarbon-gas generator, the combination of a retort provided with a seal-cup around its top, a reservoir fitting into said cup, a pipe connecting the reservoir with the retort to equalize the pressure in both, and a siphon or trap overflow to the reservoir, substantially as described.

5. In a hydrocarbon-gas generator, the combination of the sectional casing, the retort provided with a seal-cup around its top, and the detachable reservoir fitting into the seal-cup of the retort and closing the top of the latter, substantially as described.

6. The combination of the retort provided with a seal-cup around its upper end, a series of communicating vaporizing-chambers formed

of plates provided with cups and rims fitting together, as set forth, a detachable reservoir having a rim and flange fitting into the cup of the retort and top partition-plate thereof, and provided with the grated or reticulated bottom, the valve for regulating the flow of hydrocarbon into the retort, and the tubes for the introduction of liquid or other gas-producing substance, the equalizing-pipe, and the siphon or trap overflow, substantially as described.

In testimony whereof I have hereunto set my hand in the presence of two subscribing witnesses.

WILLIAM H. DOUGLASS.
